[57] CLAIM

The ornamental design for a tire, as shown and described.

DESCRIPTION

FIG. 1 is a perspective view of a tire showing our new design, it being understood that the tread pattern is repeated uniformly throughout the circumference thereof and the opposite side is the same as that shown;

FIG. 2 is an enlarged fragmentary front elevation view of the tread thereof; and,

FIG. 3 is an enlarged fragmentary front elevation view of the tread of a tire showing a second embodiment of our new design, it being understood that the tread pattern is repeated uniformly throughout the circumference of the tire as in the FIG. 1 illustration of the first embodiment and that the sides are the same as the first embodiment.
